UNITED STATES PATENT OFFICE.

ARGYLE CAMPBELL AND ALBERT E. ZIMMER, OF CHICAGO, ILLINOIS, ASSIGNORS TO
ENTERPRISE RAILWAY EQUIPMENT COMPANY, OF CHICAGO, ILLINOIS, A COR-
PORATION OF ILLINOIS.

CAR-DOOR-LOCKING MECHANISM.

Original application filed August 26, 1921, Serial No. 495,665. Divided and this application filed May 2,
1925. Serial No. 27,363.

This invention relates to improvements
in car door locking mechanisms, and com-
prises a division of the subject-matter dis-
closed in our pending U. S. application,
Serial No. 495,665, filed August 26th, 1921.

An object of the invention is to provide
a door lock or latch arrangement for a rail-
way car door, which is simple in form, rela-
tively inexpensive to make, apply and main-
tain, and which will always insure the doors
being fully closed when locked to prevent
leakage of the contents of the car while in
transit.

Another object of the invention is to pro-
vide a door locking mechanism which elimi-
nates the use of chains or equivalent flexible
conditions, and which is so arranged that
as the doors are pushed or kicked to closed
position, the mechanism will automatically
lock or latch the doors in closed position.

A still further object of the invention is
to provide a mechanism of the character
above indicated wherein a locking or latching
element is employed, which constitutes
a movable extension of a beam construction
secured to the free edge of the doors.

Other objects of the invention will more
clearly appear from the description and
claims hereinafter following.

In the drawings forming a part of this
specification Figure 1 is a side elevational
view of a portion of a hopper car showing
the invention in connection therewith, the
parts being in the condition assumed when
the doors are in closed position, and Figure
2 is a front elevational view of a part of
the structure shown in Figure 1.

Referring to the drawings the type of car
shown is one having transversely aligned
hoppers, one on each side of the center sill
construction of the car, only the outer end
of the car hopper with so much of the con-
struction necessary to show the mechanism
being illustrated. As customary, such hop-
pers are formed with triangular outer side
sheets 620, which slope slightly inwardly
and downwardly towards the center of the
car. Each of such hoppers is also provided
with a downwardly sloping hopper bottom
sheet (not shown), and the opening of each
hopper on each side of the car is adapted

to be closed by a hopper door or member 622
pivotally mounted to swing about its upper
edge on an axis extending transversely of
the car, as indicated at 623. In this type of
car, the two transversely aligned doors may
be simultaneously operated by means of a
suitable cross-brace extending along the free
edges of the doors, such a brace being shown
at 624, the same being preferably of channel
formation.

The locking mechanism contemplated by
this invention is duplicated on the door
structure at each side of the car, only one
set being illustrated in the drawing. Each
locking arrangement comprises a latching
element proper A⁶, and a fixed co-operating
member B⁶. The latching element A⁶ is
shown in the form of a bar pivoted at its
inner end on a bolt 90, supported in a suit-
able bracket 628 secured to the door and
brace 624. The fixed member B⁶ is in the
form of a casting riveted to the side hopper
sheet 620 and having its lower end extended
beyond the line of the door when the latter
is in closed position. The upper edge of
the extended end is notched so as to provide
a transverse shoulder 635 over which the
latching element A⁶ is adapted to fall to
locked position so as to bear thereagainst.
The shoulder 635 is disposed in a vertical
plane thereby presenting a bearing surface
to the element A⁶ which is at right angles
thereto when the said element is in locked
position. The extreme outer end of the ex-
tension of the member B⁶ is beveled as in-
dicated at 636 so as to provide a cam edge
for guiding the pivoted latch plate A⁶ into
position when the door is closed.

It will be noted that the latch bar cannot
fall below the channel member 624 when
the door is open, and consequently it will
always travel in the path of the inclined
edge 636. When unlocking the door the latch
element A⁶ may be swung through an arc
of 180 degrees to an inoperative position
so as to rest on the channel beam, and be
completely out of the way of the shoul-
dered bracket. Thus an operator may un-
lock one side of the door and thereafter
walk around to the other side of the car
and unlock the latch on the latter side with

assurance that the latch first opened will not accidentally fall into engagement with the corresponding shouldered bracket. The arrangement as provided in construction is exceedingly simple and strong inasmuch as the latch member A⁶ is merely a continuation of the reinforcing channel 624 beyond the plane of the side edge of the door, which latter is reinforced with an outstanding marginal flange 637 at its side edge.

In order to provide sufficient clearance for the member A⁶ to clear the said flange 637, and also to provide a suitable abutment immediately adjacent the edge of the door for 15 the latch member, the construction includes a filler portion 638 interposed between the latch member and the door, said portion 638 being riveted to the door plate as indicated at 639. The arrangement thus provides guides between which the latch member A⁶ may freely swing and yet be restrained against undue movement.

While we have herein shown and described what we now consider the preferred manner of carrying out our invention, the same is merely illustrative and we contemplate all changes and modifications that come within the scope of the claims appended hereto.

30 What we claim is:

1. In a dump car, the combination with a dumping door; of a beam extending adjacent the free edge of the door and terminating adjacent a side edge of the door; a bar pivotally mounted on said beam, said bar extending continuously from the terminus of said beam beyond the side edge of the door and constituting a longitudinally disposed supporting extension of the beam; 40 and a shouldered bracket on the car engageable with the bar on the door to maintain the door in closed position.

2. In a dump car, the combination with a dumping door, said door having an outstanding marginal flange adjacent the side edge thereof; of a beam extending adjacent the free edge of the door and terminating adjacent a side edge of said door; a bar pivotally mounted on the beam and adapted to 50 swing substantially in the plane of the door, said bar being arranged on said beam so as to extend from the end of the beam across the plane of the door flange and clear the same; and a shouldered bracket on the car engageable with the bar on the door at an angle to the plane of pivotal movement thereof to maintain the door in closed position.

3. In a dump car, the combination with a 60 dumping door; of a beam extending adjacent the free edge of the door and terminating adjacent a side edge of the door; a bracket secured to the beam and arranged within the side edge of said door; a bar pivotally mounted on the bracket, said bar be-

ing adapted to extend from said bracket beyond an edge of the door; and a shouldered bracket on the car co-operable with the bar on the door to maintain the door in closed position.

4. In a dump car, the combination with a dumping door, said door having an outstanding marginal flange adjacent the side edge thereof; of a beam extending adjacent the free edge of the door; a bar pivotally mounted on the beam and adapted to continue the beam effect across the plane of the said marginal flange of the door; means interposed between the said bar and the door for the purpose of spacing the bar outwardly from the flange; and means on the car co-operable with the bar to maintain the door in locked position.

5. In a dump car, the combination with a swinging door, said door having a reinforcement secured thereto, a shouldered bracket on the car adjacent an edge of the door; and a bar pivotally mounted on the reinforcement, said bar being adapted to be positioned either to automatically engage with the bracket when the door is moved to closed position, or to be placed in inoperative position with respect to the bracket when the door is in closed position.

6. In a dump car, the combination with a hopper having a downwardly sloping side wall; a swinging door having its side edge conforming to the slope of the side wall; a locking bar pivotally mounted on the door, said bar extending beyond the side edge of the door; and a shouldered bracket fixedly secured to the downwardly sloping side wall, said shouldered bracket being co-operable with the bar to maintain the door in closed position, said bracket having the shouldered portion disposed in a vertical plane and at right angles to the plane of the bar when the door is in closed position.

7. In a dump car, the combination with a swinging door; of a reinforcing channel beam extending along the free edge thereof; a locking bar; means for pivotally mounting said locking bar on said channel member to swing in the plane of the door; and a shouldered bracket fixedly secured to the side wall of the car adjacent a side edge of the door, said shouldered bracket being adapted to engage the free end of the bar to maintain the door in locked position.

8. In a dump car, the combination with a dumping door; of a reinforcing member extending along the free edge of the door; said member having a web outstanding from the door; a bracket carried by said web; a locking bar pivotally mounted on said bracket, said locking bar being extended beyond the corresponding side edge of the door and adapted to swing in the plane of the door; a shouldered bracket secured to the side wall of the car adjacent the side of the door, said

- shouldered bracket being adapted to receive the end of the locking bar to maintain the door in locked position.
9. In a dump car, the combination with a dumping door having a flange outstanding from the side edge of the door; of a reinforcing member extending along the free edge of the door; said member having a web outstanding from the door; a bracket carried by said web; a locking bar pivotally mounted on said bracket to swing in the plane of the door, said bar being spaced outwardly from the door to clear the flange on the door; a filler member interposed between the bar and the door, said member being extended to form a bearing for the bar adjacent the door flange; and a shouldered bracket secured to the car, said bracket being co-operable with the bar to maintain the door in locked position.
10. In a dump car, the combination with a dumping door formed of a metallic plate; of a reinforcing member extending adjacent the free edge of the door; a bracket secured to the said member; a locking bar pivotally mounted to swing in the plane of the door, said bar being interposed between the bracket and the door plate; a pivoted connection for the bar extending through the door plate and the bracket; and a shouldered bracket on the car co-operable with an end of the bar to lock the door in closed position.
11. In a dump car, the combination with a dumping door; of a reinforcing member adjacent the free edge of the door; a pivotally mounted locking member adapted to swing in the plane of the door, said mem-
- ber being disposed between guides associated with the reinforcing member on the door; and a shouldered member adjacent an edge 40 of the door co-operable with the locking member to lock the door in closed position.
12. In a dump car, the combination with a dumping door; of reinforcing means extending adjacent the free edge of the door, 45 said reinforcing means being provided with a movable extension projecting beyond the door structure, said extension being movable at an angle to the stresses upon said reinforcing means, and functioning as a continuation thereof against said stresses; and means on the car structure co-operable with the movable extension to maintain the door in closed position.
13. In a dump car, the combination with 55 transversely disposed hoppers providing dumping openings; of a plurality of pivoted doors for closing said openings; a continuous member extending along the free edges of said doors, the opposite ends of said member being provided with extensions projecting beyond the doors, said projections being movable at an angle to the stresses upon said member, and constituting continuations of said reinforcing element 60 against said stresses; and means connected with the car structure and co-operable with said extensions to lock the doors in closed position.

In witness that we claim the foregoing 70
we have hereunto subscribed our names this
29th day of April, 1925.

ARGYLE CAMPBELL.
ALBERT E. ZIMMER.
